UNITED STATES PATENT OFFICE.

WILLIAM HADDEN, OF BROOKLYN, ASSIGNOR TO THE AMERICAN RAILWAY SIGNAL COMPANY, OF NEW YORK, N. Y.

ELECTRIC RAILWAY-SIGNAL.

SPECIFICATION forming part of Letters Patent No. 278,940, dated June 5, 1883.

Application filed August 26, 1882. (No model.)

To all whom it may concern:

Be it known that I, WILLIAM HADDEN, of Brooklyn, Kings county, State of New York, have invented a new and Improved Railway-
5 Signal, of which the following is a full, clear, and exact description.

My improvement relates to the class of railway-signals employing electricity as a motive agent and using movable banners for giving
10 signals.

The improvement consists in a divided banner, the two halves of which are attached to pendulous arms operated by electro-magnets.

The object of the invention is to reduce the
15 motion of the armatures of the electro-magnets, so as to admit of having them in the stronger portion of the magnetic field.

In the drawing, A is a signal-box having the opening B, through which is displayed either
20 a clear white light or a light modified by the bisected banner C. The halves a a' of the banner C are attached to the ends of the levers b
b', fulcrumed on the pivot c and capable of swinging freely, so as to close the halves of the banner C over the opening B, or separate them,
25 so as to completely uncover the opening B, as shown in the drawing. The upper and shorter arms, d d', of the levers b b' are connected by short rods e e'
vers f f', pivoted at g g', and each carrying an armature, h. Each armature is within the influence of an electro-magnet, D, and the electro-magnets are connected in the signal-circuit, in which are placed the necessary circuit-break-

ers. The halves of the banner C close together 35 by their own gravity to give the signal, and remain closed so long as the electric circuit is open. When the circuit is closed the armatures h are drawn toward the magnet D, and through their connections move the levers b b', 40 so as to separate the halves of the banner and obscure them, leaving the opening B uncovered. By making the banner in halves I reduce the motion of the armatures employed to operate the signal, so that a smaller current 45 will suffice to operate it, and by employing tubular armature-levers I avoid the inertia of a large body of metal and render the signal more sensitive to the electric current.

Having thus fully described my invention, I 50 claim as new and desire to secure by Letters Patent—

1. In a railway-signal, the divided pendulous banner, in combination with the electro-magnets and tubular armature-levers, as herein specified.

2. In a railway-signal, the combination, with the box A, provided with the aperture B and the electro-magnets D, of the levers b b', the parts a a' of the banner C, secured to the lower 60 ends of said levers, the connecting-rods e e', and the armature-levers f f', substantially as herein shown and described.

WILLIAM HADDEN.
